HANDLE

William J. Horgan, Jr., Pittsburgh, Pa., assignor to Blumcraft of Pittsburgh, Pittsburgh, Pa.

Filed Jan. 8, 1970, Ser. No. 20,834

Term of patent 14 years

Int. Cl. D8—03

U.S. Cl. D8—166

Fig. 1

Fig. 2

Fig. 6

Fig. 3

Fig. 4

Fig. 5

FIG. 1 is a perspective view of a handle in accordance with one embodiment of my invention;

FIG. 2 is a front elevation of the embodiment shown in FIG. 1;

FIG. 3 is a top view of the embodiment shown in the previous figures;

FIG. 4 is a bottom view of the embodiment shown in the previous figures;

FIG. 5 is a rear elevation of the embodiment shown in the previous figures; and

FIG. 6 is a right side view of the embodiment shown in the previous figures.

The shading employed does not connote actual appearance, but is an expedient to best illustrate the shape of the handle.

I claim:

The ornamental design for a handle, as shown and described.
